UNITED STATES PATENT OFFICE

WILLIAM D. FERRIS, OF STERLING, ILLINOIS, ASSIGNOR TO FRANTZ MANUFACTURING CO., OF STERLING, ILLINOIS, A CORPORATION OF ILLINOIS

LATCH LOCK

Application filed October 5, 1928. Serial No. 310,516.

This invention relates to door latches, and more particularly to latches of the kind that have a pivoted latch bar that swings up and down, pivoted on the door, and have a stationary strike piece which is ordinarily secured to the door frame, whereby the strike piece is engaged by the latch bar, when the door is closed, and whereby the door is thereby automatically latched in closed position.

Generally stated, the object of the invention is to provide a novel and improved construction whereby said latch bar may be raised, to disengage it from the strike piece, thereby to unlatch the door, by the insertion of a key in a key hole formed in the means forming in effect the axis or pivot of the latch bar, and by turning said key to partially rotate the said pivot or axis means, thereby utilizing the key as a thumb piece or handle by which to operate the pivoted latch bar and thereby unlatch the door.

It is also an object to provide certain details and features of construction and combinations tending to increase the general efficiency and the desirability of a key-operated pivoted latch-bar mechanism of this particular character.

To the foregoing and other useful ends, the invention consists in the matters hereinabove set forth and claimed, and shown in the accompanying drawing, in which,—

Fig. 1 is an inside face view or elevation of a portion of a door, and of the adjacent portion of the door frame, showing the same equipped with the pivoted latch-bar mechanism embodying the principles of the invention.

Fig. 2 is a horizontal section on line 2—2 in Fig. 1.

Fig. 3 is a vertical transverse section on line 3—3 in Fig. 2.

Fig. 4 is a perspective of the plate which forms the cover for said mechanism, which plate is secured to the inner side of the door, as shown in Fig. 1 of the drawings.

Fig. 5 is a perspective of the so-called strike piece that is provided for engaging the latch bar, and which is secured in stationary position to the adjacent portion of the door frame.

Fig. 6 is an outer face view of the key-hole portion of the latch mechanism.

Fig. 7 is a view similar to Fig. 3, but on a larger scale, and with the key-operated mechanism shown in vertical section.

Fig. 8 is a detail section on line 8—8 in Fig. 2.

Fig. 9 is a detail section on line 9—9 in Fig. 7, with certain portions or parts omitted.

As thus illustrated, the invention comprises a more or less cylindrical barrel 1 set in a recess formed in the door 2, said barrel having an outer flange 3 bearing upon the outer side of the door. A sheet-metal plate 4 has a struckout portion 5 and is secured by screws 6 inserted through holes 7 in said plate, into the inner side of the door. In addition, said plate has a bent or right-angle end portion 8 provided with screw holes 9 for the insertion of screws into the edge portion of the door. Said plate 4 also has an opening 10 which forms a bearing for the end portion of the square spindle 11, which latter has a compensating pivot at 12 in the inner end portion 13 of the cylindrical or round axis member 14 mounted to rotate in the barrel 1 previously mentioned. Said barrel has a fixed stop pin 15, on the face or inner end of said barrel, and the portion 13 is cut away to form shoulders 16 and 17 for engagement with said stop pin, thereby to limit the rotation of the axis member 14, in a manner that will be readily understood. A latch bar 18 has one end portion provided with a square hole 19 through which the spindle 11 extends, this latch bar being thus mounted to swing up and down between the portion 5 and the outer face of the body portion of the plate 4 previously mentioned. Screws 20 are inserted through the plate 4 and into the barrel 1, thus holding the latter in position.

Obviously, by rotation of the member 14, or partial rotation thereof, the latch bar 18 will be raised, and for this purpose the member 14 is provided with a key hole 21 shaped to fit a certain key 22, whereby the latter can be used as a thumb piece or handle by which to partially rotate the member 14 and thus raise the latch.

The strike piece 23 is secured by screws 24

to the door frame 25, and is provided with a right-angle or bent portion 26 which forms a stop for the door 2, as shown in Fig. 2 of the drawing, and which effectually closes the joint 27 between the door frame 25 and the door jamb 28, thus making it impossible to insert a knife or thin instrument through said joint and under the latch bar 18, in an effort to open the door without a key. The portion 26 can be set into the door jamb 28, so that the exposed surface of the portion 26 will be flush with the inner side of the door jamb, so that the door will close tightly against said door jamb. Furthermore, it will be seen that this strike piece has upper and lower engaging portions 29 and 30, with upper and lower notches 31 and 32, at the inner ends of these engaging portions, for receiving the swinging end portion of the latch bar 18 previously mentioned. In this way, the strike piece 23 can be employed on either a right or left door, as it can be turned upside down from the position shown in Fig. 5 to bring the portion 29 and the notch 31 into operative relation to the latch bar, if such is necessary or desirable. The plate 4 and all of the elements attached thereto can also be turned upside down, or reversed, for either a right or left door, and hence the pivoted latch-bar mechanism can be used in its entirely upon either a right or left door without any changes in the construction thereof.

It is obvious that each and every pivoted latch-bar mechanism embodying the invention may have a key 21 of different form or shape, so that no two latches will have the same shape or form of key hole, and a key to fit each and every latch mechanism can be provided. Thus the key has the double function, so to speak, of operating the pivoted latch and unlocking the door.

It will be seen that with the substantial length shown for the spindle 11, and with screw holes of sufficient depth in the barrel 1, for the screws 20, the distance between the flange 3 and the plate 4 may vary somewhat, depending upon the thickness of the door. The spindle 11 rotates in the hole 10 as a bearing, and the spindle can slide endwise in the hole 19, when the parts are assembled, thus permitting application of the latch mechanism to doors of different thicknesses. By pivoting the square or polygonal spindle 11 at 12, on the portion 13, the assembling of the parts is somewhat facilitated, and there can be more or less inexact alignment, due to the shape or formation of the wood door, or of the parts of the mechanism, without interfering with the easy coupling together of the barrel 1 and the plate 4, and without causing the movable parts to bind in the operation of the latch mechanism.

When the door is closed, the lower edge of the latch bar 18 strikes one or the other of the engaging portions 29 or 30, depending

upon the position of the mechanism, and the latch bar rides up the incline of such engaging portion until it drops into the notch 31 or 32, depending upon whether the door is a right or left door. To open the door, the key 22 is inserted in the key hole 21, and given a twist or turn in one direction to lift the latch bar out of the notch 31, or the notch 32, so that the door can then be freely opened.

Of course, without some sort of means to prevent, the member 14 might be turned with a screw-driver or other instrument, by an unauthorized person; but to prevent this, key-operated tumbler mechanism, of a well known form, is employed, which briefly is as follows: This mechanism is shown in Figs. 7, 8 and 9, and comprises a series of pairs of vertical movable tumblers 33, which are slotted differently to provide vertical slots through which the key may be inserted, as shown. The barrel 1 is provided with upper and lower longitudinal grooves 34 and 35 to receive the upper and lower ends of the tumblers, as the tumblers are pushed one way or the other by the insertion and withdrawal of the key. When the key is withdrawn, the tumblers, or some of them, drop down by gravity into the groove 35, thus effectually locking the member 14 against rotation. One pair of tumblers has the well known coiled spring (not shown) applied thereto for causing one member of the pair to move up into the groove 34 and the other member to move downward into the groove 35, positively, when the key is withdrawn. The part 13, it will be seen, is in the form of a collar keyed on the inner end of the member 14 by the pin 12 previously mentioned. By forcing out this pin, the collar 13 can be removed, and the tumbler mechanism can be taken apart. But any suitable form of lock mechanism can be employed, capable of lifting the latch bar when the key is twisted or turned, without departing from the spirit of the invention.

It will be seen that by withdrawing the screws 20, the axis member 11 and parts 1 and 3 can be withdrawn from the outer side of the door, thereby releasing the latch bar 18 from the inner side of the door, when it is desired to remove the mechanism from the door.

It will be seen that the pivotal connection 12, between the square spindle 11 and the member 1, provides flexibility and relative motion, whereby there is some compensation for any inaccuracy in the fitting of the parts together, or any failure to exactly align the different parts. Notwithstanding any such errors or defects in construction, the pivotal connection will permit free rotary motion of the lock mechanism, without any binding effect that might result if the spindle 11 were rigid with the lock mechanism member 1, as will be readily understood. In this way

the lock and spindle are easily pushed through the door, and through the latch bar, and are easily removed or withdrawn, for there is no binding action either in the assembling or the operation of the latch mechanism thus provided.

It is evident, from the drawing and the foregoing description, that the latch bar 18 can not swing up and down about its pivot unless the key 22 is in the lock, for when the key is not thus inserted, the tumblers, as previously explained, hold the cylindrical barrel against rotation. Obviously, therefore, when the door is open, the key can be left in the lock, and when the door is slammed shut, the latch bar 18 will be free to rise over the cam 30, and to thereby assume a latching position. It will also be seen, from the foregoing, and from the drawing, that the spindle 11 has direct non-rotary engagement with the latch bar 18, and that withdrawal of the spindle from the squared hole 19 in the latch bar, of necessity leaves the latter free to be removed endwise from the guard 5 forming a part of the back plate 4 by which the lock mechanism is held in place. In other words, the latch bar 18 is supported entirely by the spindle 11, and withdrawal of the latter leaves the latch bar without any pivotal support or mounting whatever.

The barrel portion 13 has its inner end provided with a transverse slot in which the flattened end of the spindle 11 is disposed, as shown in Figs. 2, 7 and 8, and the pin 12 extends through this slot and the said flattened end portion of the spindle, thereby to removably hold the spindle in operative engagement with the slot, whereby it is the side walls of the slot that communicate the torque to the spindle 11, when the barrel is rotated by the key, as well as or even more so than the said removable pin, as with this slot formation there is practically very little torque strain on the said pin. In addition, the guard plate 4, being provided with the portion 5, is in effect provided with two aligned slots, one at each end of the portion 5, in which the latch bar 18 is free to move up and down, and in which the said latch bar is displaceable endwise when disengaged from the spindle.

What I claim as my invention is:

1. A door latch adapted to be both unlocked and operated by a removable key, comprising lock mechanism inserted through the door from the outside, having a spindle projecting from the inner side of the door, adapted to be both unlocked and rotatably operated by the insertion of a key therein, a latch bar having direct non-rotary loose engagement with the inner end portion of said spindle, so that said spindle forms the supporting pivot or axial support for the latch bar, said latch bar being adapted for engagement

with a strike piece on the doorway, and means for removably fastening said mechanism in place, whereby withdrawal of said mechanism from the outer side of the door will disengage the latch bar from its pivotal support, comprising a plate secured to the inner side of the door and provided with a guard covering an intermediate portion of said latch bar, thereby to normally maintain said loose engagement of the latch bar with the spindle, whereby said latch bar is removable by endwise displacement thereof after disengagement from said spindle. 70

2. A door latch adapted to be both unlocked and operated by a removable key, comprising lock mechanism inserted through the door from the outside, having a spindle projecting from the inner side of the door, adapted to be both unlocked and rotatably operated by the insertion of a key therein, a latch bar having direct non-rotary loose engagement with the inner end portion of said spindle, so that said spindle forms the supporting pivot or axial support for the latch bar, said latch bar being adapted for engagement with a strike piece on the doorway, and means for removably fastening said mechanism in place, whereby withdrawal of said mechanism from the outer side of the door will disengage the latch bar from its pivotal support, comprising a guard plate fastened to the inner side of the door, partially covering said latch bar, thereby to maintain said normally loose engagement of the latch bar with the spindle, said guard plate having 100 a plurality of screws forming the means for detachably holding said mechanism in place. 100

3. A door latch adapted to be both unlocked and operated by a removable key, comprising lock mechanism inserted through the door from the outside, having a spindle projecting from the inner side of the door, adapted to be both unlocked and rotatably operated by the insertion of a key therein, a latch bar having direct non-rotary loose engagement 110 with the inner end portion of said spindle, so that said spindle forms the supporting pivot or axial support for the latch bar, said latch bar being adapted for engagement with a strike piece on the doorway, and means for removably fastening said mechanism in place, whereby withdrawal of said mechanism from the outer side of the door will disengage the latch bar from its pivotal support, comprising a guard plate secured to the inner side of 120 the door, shaped to provide two oppositely aligned slots for the latch bar, thereby maintaining said normally loose engagement of the latch bar with the spindle, in which the latch bar is movable up and down, and in which the latch bar is displaceable endwise after disengagement from said spindle. 125

Specification signed this 1st day of October, 1928.

WILLIAM D. FERRIS. 130
